DISHWASHING MACHINE

Robert Burkle, North Bergen, N. J., assignor of
one-half to Richard Merrifield, New York,
N. Y.

Application June 4, 1932, Serial No. 615,287

9 Claims. (Cl. 141—9)

This invention relates to new and useful improvements in an automatic dish washing and drying machine designed particularly for use in restaurants, lunch wagons, glass pantries and domestic kitchens.

It is an object of this invention to construct the body of the device in a manner so that it is compact and adapted for efficiency in operation and speed in use.

10 Furthermore, it is proposed to construct the top of the wash chamber with a slope or the like to draw in water to the outer sides and not drip over the dishes after washing is completed.

Furthermore, as another object of this invention it is proposed to provide the body with a sliding door adapted to expose half of the top and complete front of the wash chamber giving access to all dishes without removing the dish basket and making for a quick circulation of air 20 around the dishes to facilitate drying.

Another one of the objects is the arrangement of a few bends upon the body and sliding door previously mentioned to form simplified watertight joints between the door and the back of the wash chamber without the addition of extra parts.

It is also contemplated to provide a dish basket which is particularly adapted to efficiently hold the dishes in the washing machine for proper washing.

30 Another one of the objects of this invention is the construction of a device of the class described which is of simple durable construction, dependable in use and efficient in operation and which can be manufactured and sold at a reasonable cost.

For further comprehension of the invention, and of the objects and advantages thereof, reference will be had to the following description and 40 accompanying drawings, and to the appended claims in which the various novel features of the invention are more particularly set forth.

In the accompanying drawings forming a material part of this disclosure:

45 Fig. 1 is a front elevational view of a washing machine constructed according to this invention, with portions broken away to disclose the interior construction.

50 Fig. 2 is a top plan view of the machine, with portions broken away to disclose interior part.

Fig. 3 is a fragmentary side elevational view of the machine with parts broken away in a manner so as to disclose in detail the vacuum drying system and the starting device on the door joint.

The dish washing machine, according to this invention, comprises a body 10 attached to a concaved bottom 11 formed with a recess portion 12 to which a drain pipe 13 is connected for connection with some drain system. The front of the body 10 is open and normally closed by a sliding door 14. This door is supported on rollers 14' which are secured between a circularly arranged angle iron 15 and the body 10. The angle iron 15 is supported by radial pins with 10 said body. The rollers 14' are mounted on said pins. The angle iron 15 is also adapted for receiving a dish basket 16. The door 14 is pivoted on top center under casting 21. Spraying elements 17 and 18 are respectively located in the 15 vicinity of the bottom and the top of the body and are adapted to spray towards each other so as to wash dishes within the basket 16. The body 10 is supported upon legs 19 adapted to rest upon some flat surface. The front portion of 20 the body 10 is of circular contour while the rear portion is square as clearly illustrated in Fig. 2.

The door 14 has a top portion 14^a for closing the top of the body which is cut away in semi-cylindrical fashion. The top of the door 14^a 25 and top of wash chamber is formed with an inverted conical portion 20 arranged so as to cause the water to run to the sides of the wash body instead of dripping down upon the basket of dishes, especially when the latter are drying. 30

Each of the spraying elements 17 and 18 is connected with a supply of liquid through the piping system 23. This piping system connects up with a motor driven pump 24.

The door 14 and the jamb portion on the body 35 10 are constructed in a manner so as to prevent the water from the interior supplying or reaching the exterior. In detail, the construction comprises a bulged edge 40 upon the edge of the door adapted to engage a bent bulged portion 41 upon 40 the body 10. At the other edge 42 on the back of door a similar construction is arranged whereby a bent edge 43 from the door engages a bent edge 44 from the body and insures a tight joint. The door 14 is provided with a heat insulated handle 136 for convenience in moving. A strainer 137 is shown disposed within the recessed portion 12 of the wash chamber so as to prevent large pieces from passing through the drain pipe 13 with the possibility of stuffing it. 50 The strainer is also designed to prevent a whirlpool over drain pipe 13. Occasionally it is necessary that the strainer 137 be removed and cleaned.

While I have shown and described the preferred embodiment of my invention, it is to be under- 55

stood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In an automatic dish washing and drying machine, a cylindrical body having a bottom, a horizontal circular flange within said body spaced from the bottom of said body and slightly from the sides and attached upon the sides, rollers rotatively mounted between said body and flange, a door over an opening in said body and slidably resting upon said rollers, and a dish basket on said flange for holding dishes.
2. In an automatic dish washing and drying machine, a cylinder body having a bottom, a horizontal circular flange within said body spaced from the bottom of the body and slightly from the sides and attached upon the sides, elements for supporting a door arranged between said body and flange, a door over an opening in said body and resting upon said elements, and a dish basket on said flange for holding dishes.
3. In an automatic dish washing and drying machine, a cylindrical body, a horizontal circular flange within said body and slightly spaced from the sides thereof, means connecting the flange and body for supporting the flange, rollers mounted on said supporting means, a door over an opening in said body and resting on and operable upon said rollers, and a dish basket on said flange for holding dishes.
4. In an automatic dish washing and drying machine, a cylindrical body, a horizontal circular flange within said body and slightly spaced from the sides thereof, means connecting the flange and body for supporting the flange, rollers mounted on said supporting means, a door over an opening in said body and resting on and operable upon said rollers, and a dish basket on said flange for holding dishes, said means for supporting the flange comprising pins attached on the body and on the flange.
5. In an automatic dish washing and drying machine, a cylindrical body, a horizontal circular flange within said body and slightly spaced from the sides thereof, means connecting the flange and body for supporting the flange, rollers mounted on said supporting means, a door over an opening in said body and resting on and operable upon said rollers, and a dish basket on said flange for holding dishes, said circular flange having a horizontal top portion connecting with a vertical side, and said supporting means being connected between the vertical side and the body.
6. In an automatic dish washing and drying machine, a cylindrical body, a horizontal circular flange within said body and slightly spaced from the sides thereof, means connecting the flange and body for supporting the flange, rollers mounted on said supporting means, a door over an opening in said body and resting on and operable upon said rollers, and a dish basket on said flange for holding dishes, said means for supporting the flange comprising pins attached on the body and on the flange, said pins extending radially of the circular flange.
7. In an automatic dish washing and drying machine, a vertical cylindrical body, a horizontal cylindrical flange within said body and slightly spaced from the sides thereof, means connecting the flange and body for supporting the flange, rollers mounted on said supporting means, a door within said body having a semi-cylindrical peripheral portion over an opening in said body and connecting with a top face portion engaged in a bearing at the vertical center of the said body, the semi-cylindrical peripheral portion of said door resting and operable upon said rollers, and a dish basket on said flange for holding dishes.
8. In an automatic dish washing and drying machine, a vertical cylindrical body, a horizontal cylindrical flange within said body and slightly spaced from the sides thereof, means connecting the flange and body for supporting the flange, rollers mounted on said supporting means, a door within said body having a semi-cylindrical peripheral portion over an opening in said body and connecting with a top face portion engaged in a bearing at the vertical center of the said body, the semi-cylindrical peripheral portion of said door resting and operable upon said rollers, and a dish basket on said flange for holding dishes, the door being fixedly guided at the top on its vertical axis so that it may function in a circular path.
9. In an automatic dish washing and drying machine, a vertical cylindrical body, a horizontal cylindrical flange within said body and slightly spaced from the sides thereof, means connecting the flange and body for supporting the flange, rollers mounted on said supporting means, a door within said body having a semi-cylindrical peripheral portion over an opening in said body and connecting with a top face portion engaged in a bearing at the vertical center of the said body, the semi-cylindrical peripheral portion of said door resting and operable upon said rollers, and a dish basket on said flange for holding dishes, said means for supporting the flange comprising pins attached on the body and on the flange.

ROBERT BURKLE.
